J. W. DOREMUS,

GAME.

APPLICATION FILED MAY 11, 1921.

1,383,610.

Patented July 5, 1921.

Inventor

Isaac W. Doremus
By his Attorney

Clarence G. Campbell

UNITED STATES PATENT OFFICE.

ISAAC W. DOREMUS, OF WEST ENGLEWOOD, NEW JERSEY.

GAME.

1,383,610.

Specification of Letters Patent.

Patented July 5, 1921.

Application filed May 11, 1921. Serial No. 468,682.

To all whom it may concern:

Be it known that I, ISAAC W. DOREMUS, a citizen of the United States, residing at West Englewood, in the county of Bergen and State of New Jersey, have invented certain new and useful Improvements in Games, of which the following is a specification.

My invention relates to a game, and more particularly to a combination of elements 10 in a game, as will be more fully hereinafter pointed out.

There have been many games where a group of objects were adapted to be arranged in a position for knocking the same 15 down by means of a projectile thrown or shot thereat. But my device is so arranged that the objects are weighted in the lower part or tail so that they balance perfectly on a flexible or elastic member, and they 20 can therefore only be knocked off by a direct hit of the object or flexible member. The objects are also usually in motion, because they are balanced on the flexible member which readily vibrates.

25 In the drawing, which is a perspective of the preferred form of my device, 1 is the base member having holes 2 adapted to receive members 3, to which are rigidly secured cross bars 4, which are slotted at 5 so 30 as to receive a flexible or elastic member 6, on which are adapted to be placed objects 7 having tail members 8 which are weighted so that the objects 7 will rest firmly on the flexible member 6 at 9, which is cut away 35 for that purpose.

Secondary base members 10 have holes 11 into which uprights 12 are adapted to be set, and a net 13 is secured to said uprights 12 in slots 14 in said uprights 12.

40 An elastic or other suitable flexible material may be used for the flexible member 6.

Upright members 3 and 12 are all adapted to be removed from their respective bases, so that the entire device may be 45 packed in a compact manner.

The various members are adapted to be

set up for use as shown in the drawing, so that the net will serve as a backstop for the projectiles thrown or shot thereat. The well-known pop gun or other means (not 50 shown) may be used for this purpose.

Variations may be made in the device described and shown herein without departing from the spirit of my invention.

I claim:

1. In a game the combination of a base member supporting upright rigid members, around the upper ends of which is strung a flexible member on which is supported a group of objects resting in balanced position, together with a number of secondary base members each supporting perpendicular uprights on which a net is secured, thereby serving as a backstop for missiles projected at said balanced objects. 55

2. In a game the combination of a base member supporting upright rigid members having cross trees, around which is stretched an elastic and on which is balanced a group of objects. 60

3. In a game the combination of a base member supporting upright rigid members, around the upper ends of which is strung a flexible member on which is supported a group of objects resting in balanced position. 70

4. In a game the combination of a base member supporting upright rigid members, around the upper ends of which is strung a flexible member on which is supported a group of objects resting in balanced position and adapted to be knocked therefrom by missiles projected thereat. 80

5. In a game the combination of a base member supporting upright rigid members, around the upper ends of which is strung a flexible member on which is supported a group of objects resting in balanced position, and which are so weighted in the tail members as to facilitate the balance thereof. 60 55

In testimony whereof I affix my signature.

ISAAC W. DOREMUS.
